UNITED STATES PATENT OFFICE.

EDWIN W. GROVE, OF ST. LOUIS, MISSOURI.

ATTACHMENT FOR RAZORS.

1,169,637.

Specification of Letters Patent. Patented Jan. 25, 1916.

Application filed January 12, 1915. Serial No. 1,817.

To all whom it may concern:

Be it known that I, EDWIN W. GROVE, a citizen of the United States, residing at St. Louis, State of Missouri, have invented 5 new and useful Improvements in Attachments for Razors, of which the following is a specification.

This invention relates to improvements in attachments for razors, proposing an attachment for the purpose of applying liquid medicament or healing solution to the face during the operation of shaving.

The object of the invention is to provide an attachment for the purposes stated which shall be simple in its structural nature, inexpensive, readily applicable to any existing type of razor, and highly efficient for the purposes in view.

The invention, briefly stated, comprises a 20 plate or similar element provided with means for its attachment in spaced relation to a razor blade and employed to confine an absorbent pad of cotton or felt which is dipped in the liquid medicament or healing solution and which applies said medicament or solution to the face in connection with the operation of shaving.

An embodiment of the invention is illustrated in the accompanying drawings, in 30 which:

Figure 1 is a perspective view of a Gillette razor with the improved attachment fitted thereon; Fig. 2 is a side elevation of the razor, showing the attachment in section; 35 Fig. 3 is a detail perspective view of the attachment as designed for Gillette razors; Fig. 4 is a longitudinal sectional view through the blade, holder and guard of a Gillette razor, showing the present attachment in operative relation; Fig. 5 is an elevation of a razor blade of ordinary construction to which a suitable form of the attachment is applied; and Fig. 6 is a cross-sectional view of the razor blade and attachment shown in Fig. 5.

Similar characters of reference designate corresponding parts throughout the several views.

The attachment consists of a plate 1 which, when applied to the Gillette razor or to razors of the Gillette type, is located adjacent the back A of such razor in spaced relation to said back and preferably has a curved cross-section conforming to the curvature of said back. Any convenient means for applying the attachment may be pro-

vided. Preferably, however, the plate 1 has at its ends spring fingers 2 provided at their inner sides with lugs 3 which engage under the guard B of a Gillette blade and thereby 60 secure the attachment in position. The spring fingers 2 are provided at their outer sides with other lugs 4 which serve as finger pieces to permit the ready manipulation of the fingers 2 to effect their engagement with 65 and disengagement from the guard B. The length of the fingers 2 is selected whereby the plate 1 will be suitably spaced from the back A. It is contemplated that a space of about one-eighth of an inch in width shall 70 intervene between the plate 1 and the back A. The said space is taken up by a filler or pad 5 of cotton, felt, or other absorbent material suitable for the purposes in view. In applying the attachment, the pad 5 is first 75 positioned against one side of the plate 1 and thereafter the plate 1 is secured to the razor by engaging its spring fingers 2 with the guard B in the manner stated, the pad being confined with reasonable security be- 80 tween said plate and the back A. In connection with the operation of shaving, the razor is dipped into the liquid medicament or healing solution and held sufficiently long to insure the measurably thorough saturation 85 of the pad 5. When the razor is used for shaving purposes, the angle at which it is held insures that the exposed edge of the pad 5 shall contact with the skin in the rear of the cutting edge of the razor. In this 90 way, liquid medicament or healing solution is applied to the face continuously during the shaving operation, and inasmuch as the razor is held with considerable pressure against the face, and the skin is drawn taut 95 during the shaving operation, the liquid medicament or healing solution is efficiently rubbed into the skin by the pad.

The size of the pad is such that it can absorb a suitable quantity of the liquid 100 medicament or healing solution to render it unnecessary to repeatedly dip said razor in the solution during a single shaving operation. The pad projects very slightly be- 105 yond the side edges of the plate 1 and except for such projecting portions is entirely covered by said plate, the latter thus not only confining the pad in its proper position, but preventing undue evaporation of the liquid medicament or healing solution. 110

In Figs. 5 and 6, the attachment is shown in a form adapted for razor blades of ordi-

nary construction. In this case, the plate 1, which, as in the preceding instance, has a length equal to the length of the cutting edge of the blade, is provided along its 5 upper edge with in-turned spring fingers 2^a which engage over the back edge of the razor and bear frictionally against the side of the razor opposite that which is adjoined by the plate 1. The plate 1 is of less depth 10 than the blade and preferably has a cross-sectional curvature opposite to the surface curvature of that side of the blade which it adjoins in order that the space intervening between said plate and the blade may 15 be of less width adjacent the edge of said plate than adjacent the center thereof, whereby the pad 5 will be securely held in position, as will be obvious from Fig. 6.

The device may be made in forms which 20 will be appropriate for its attachment to the various types of razors commonly employed and may be readily fitted to and removed from such razors. Its use in no way interferes with the efficiency of the shaving operation, but, on the other hand, shortens the operation by eliminating the necessity for going over the face, after the shaving has been completed, with a liquid medicament or healing solution for the purpose of soothing the skin. Furthermore, in view of the fact that the liquid medicament or healing solution is applied to the face during the shaving operation under considerable pressure and while the skin is drawn taut, the application of such solution by the use of the present attachment is more efficient than is the case where such solution is merely applied to the face with the hands as is customary.

Having fully described my invention, I claim:—

1. The combination with a razor blade of an attachment therefor comprising a plate for confining an absorbent pad in a position whereby a longitudinal edge of said pad

will adjoin the cutting edge of the razor blade along a line in the rear of said blade and means carried by said plate for holding it in spaced relation to that side of the razor blade which is adjoined by said pad. 50

2. The combination with a razor blade of an attachment therefor comprising a plate for confining an absorbent pad in a position whereby a longitudinal edge of said pad will adjoin the cutting edge of the 55 razor blade along a line in the rear of said blade and spring fingers carried by said plate for holding it in relation to the razor blade.

3. The combination with a razor blade of 60 an attachment therefor comprising a plate for confining an absorbent pad in a position whereby a longitudinal edge of said pad will adjoin the cutting edge of the razor blade along a line in the rear of said blade, 65 means carried by said plate for holding it in relation to the razor blade, and an absorbent pad confined under said plate and covered by said plate except for an operative edge portion which projects slightly beyond the 70 plate.

4. The combination with a razor blade of an attachment therefor comprising a plate for confining an absorbent pad in a position whereby a longitudinal edge of said pad 75 will adjoin the cutting edge of the razor blade along a line in the rear of said blade, spring fingers carried by said plate for holding it in relation to the razor blade, and an absorbent pad confined under said plate 80 and covered by said plate except for an operative edge portion which projects slightly beyond the plate.

In testimony whereof I have hereunto set my hand in presence of two subscribing witnesses. 85

EDWIN W. GROVE.
